CHESTER H. BRASELTON AND FRED M. CARROLL, OF DAYTON, OHIO, ASSIGNEES, BY
MESNE ASSIGNMENTS, TO WOLVERINE SPARK PLUG COMPANY, INC., A CORPO-
RATION OF NEW YORK, (INCORPORATED IN 1916.)

SPARK-PLUG.

1,269,782.

Specification of Letters Patent. Patented June 18, 1918.

Application filed August 17, 1914. Serial No. 857,113.

To all whom it may concern:

Be it known that we, CHESTER H. BRASELTON and FRED M. CARROLL, citizens of the United States, residing at Dayton, in the county of Montgomery and State of Ohio, have invented certain new and useful Improvements in Spark-Plugs, of which we declare the following to be a full, clear, and exact description.

10 This invention relates to spark plugs for internal combustion engines and particularly to the means embodied in spark plugs for fastening the electrode carrying insulator in place in the bushing or body portion of the plug. It also has to do with a novel manner of wiring for the plug and arrangement of a second electrode carried by the insulator.

20 A main object of this invention is to provide for a quick or convenient removal of the insulator from the bushing in which it is seated and for a quick or convenient replacement therein all without the use of a wrench or other tool as is usually required.

25 It is also an object of this invention to use a means for fastening the insulator in place in the bushing which is of a somewhat yielding or elastic nature so that in service it may yield more or less in places required 30 to take up occurring variations in the different parts as will be present in them when making the plug in quantities, yet at the same time effecting a sufficiently strong pressure on the insulator to hold it in an air 35 tight manner against its seat in the bushing so as to prevent escape of compressed gases from the cylinder through the plug.

The invention embodies when its principle is broadly considered, the principle of the 40 spark plug described in application Serial Number 800161, filed November 10th, 1913 by Herman F. Sadgebury, for an invention in spark plugs, but it shows improvements thereover in several respects, for example 45 in the yielding or elastic nature of the insulator fastening means above referred to, in the provision for a preliminary auxiliary adjustment of the fastening means before the same is finally operated to clamp the 50 insulator to its seat, thus to permit a greater range of tolerance in making the different parts and thereby lessen the manufacturing cost of the article, and in the design of the present plug by which the fastening means

for the insulator is securely fastened to the 55 insulator at all times thereby eliminating what would otherwise be an extra loose part easily misplaceable and lost when the plug is disassembled. The present design is further an improvement over the design of the 60 above mentioned pending application as regards the particular mounting of the electrodes in the insulator the form shown in this application showing the two electrode wires running parallel to the longitudinal 65 axis of the insulator which permits of cheaper manufacture of the insulator particularly when making the same of porcelain which is in common use for spark plug insulators.

70 With the above and other incidental objects in view our invention further consists in various novel details of construction and design which will now appear in a detailed description of the preferred form of the invention shown in the accompanying drawings which form a part of this application and in which,

75 Figure 1 is a view of the completed plug showing it one-half in longitudinal section 80 and one-half in elevation.

Fig. 2 is a perspective view of the bushing of the plug.

Fig. 3 is a view in elevation of the insulator of Fig. 1 with the fastening member 85 attached.

Fig. 4 is a view of the fastening member alone.

Fig. 5 is a sectional view of the fastening member taken on the line a—a of Fig. 4. 90

Fig. 6 is a view of a modified form of fastening member.

Fig. 7 is a sectional view of this modified form of bail taken on the line F—F of Fig. 6 looking in the direction of the arrow. 95

Fig. 8 is a view of a slightly modified form of insulator.

Fig. 9 is a view partly in section, of a modified form of plug in which the fastening member is not permanently engaged with 100 the insulator but engages the same when in place, only on a shoulder on the insulator.

Fig. 10 is a view of a further modified form of plug in which the fastening member acts on the insulator through the medium of a separate sleeve, the bushing being partly cut away to show the relative construction of the parts.

Fig. 11 shows the separate sleeve of Fig. 10 with the fastening member attached.

Fig. 12 shows a plug in which the bushing is omitted, the insulator seating directly in an opening in the engine casing.

In the drawings 1 is the plug bushing externally shouldered at 2 and threaded at 3 for detachable engagement in a threaded opening in the engine casing. The bushing 10 is hollow and is provided with an interior upwardly facing shoulder 4. The insulator 5 is provided intermediate its ends with an exterior downwardly facing shoulder 6 adapted when the insulator is in place in the 15 bushing, to rest in an air tight manner on the internal shoulder 4 of the bushing. The insulator carries a central electrode 7 projecting at its lower end from the insulator and stopping flush at its upper end with the 20 insulator proper. A metallic cap 8 is fast to the upper end of the insulator covering the same and electrically connecting with the upper end of the electrode 7. The cap is provided with a threaded stud carrying 25 a binding nut 9 serving to securely receive and hold the end of a circuit wire conveying a current of electricity to the plug. The insulator may carry but one electrode or it may carry both. In Figs. 1, 3, 8, 10 and 12 30 two electrodes are shown carried by the insulator while in Fig. 9 the insulator appears carrying but one. In this latter figure a second one can conveniently be added by merely covering the surface of the upper 35 shoulder on the insulator with a metal band and running the other electrode shown in the other views to electrically connect with said band. In the views showing both electrodes carried by the insulator the second 40 one is designated by reference character 10 and the spark is of course to jump between the lower ends of the electrodes 7 and 10. If but one electrode is carried by the insulator the other is of course to be carried by 45 the bushing 1 at its lower end as shown at 11 in Fig. 9 and the spark is of course to jump between this electrode 11 and the lower end of the central electrode 7. Where the insulator carries both electrodes the second one 50 is preferably electrically connected with the bushing through the fastening member which is preferably made of metal and when holding the insulator in place in the bushing, is in engagement with the metallic bushing as well as with the second electrode 55 or some conducting material electrically connected with the second electrode, as will all clearly appear from the hereinafter contained description of the construction in this 60 respect.

As stated above in the objects provision is made in this invention so that the insulator with its one or two electrodes which it carries, as the case may be, may be conveniently and quickly secured in place in the

bushing and just as quickly and conveniently removably therefrom for such purposes as cleaning, inspecting, or adjusting the electrodes, and all without the necessary use of a wrench or other tool. We provide 70 for all this through the use of our novel fastening member which we use to secure the insulator in place in the bushing against its seat therein in an air tight manner. To accomplish these results we provide in the 75 upper end of the bushing wall and preferably 180 degrees apart two slots each having an entrance portion running generally in the direction of the longitudinal axis of the bushing and a second portion running generally in a plane at right angles to the axis of the bushing though said second portions are preferably inclined slightly to such plane so as to approach the lower end of the bushing as they extend away from the entrance portions of the slots. In Fig. 2 the entrance portions of the slots are designated 12 and from the lower ends of these which, as stated, are 180 degrees apart, the cam portions extend around the bushing in the 90 same angular direction and correspondingly downwardly toward the lower end of the bushing for purposes hereinafter appearing. These portions may approach the lower end of the bushing uniformly or they may approach it variably but in either case corresponding portions of the two slots should approach the lower end of the bushing correspondingly. As will be obvious later the second portions of the slots may if desired, 100 be located wholly in a plane at right angles to the axis of the bushing. In the drawings these portions are shown inclined and are numbered 13. So far as the operation of the plug is concerned it is only necessary 105 that the upper surfaces of these cam portions of the slots should be downwardly inclined as it will be obvious from later description of the operation that only the upper surfaces of these portions of the slots are 110 engaged with the fastening member when fastening the insulator in the bushing by the latter.

The above mentioned slots in the bushing are, as stated, for coöperation with the fastening member which is used to fasten the insulator in the bushing. The form of fastening member shown in the assembled plugs of the drawings, is shown in elevation in Fig. 4 and in section in Fig. 5. The fastening member in this form is shown made from a wire or rod of circular cross section, bent first into U shape and then having its ends turned inwardly as shown. In the drawings the main part of this fastening 115 member is designated 14 and its inwardly turned ends 15. Portions of the alined inwardly bent portions 15 are then knocked off center correspondingly taking a separate alinement than that of the outer por- 120 125 130

tions 15, and being characterized in the drawings 16, these alined portions 16 being connected with the alined portions 15 by short connecting portions 17. From this 5 it will be seen that the portions 16 while in alinement, are carried eccentrically by their corresponding alined portions 15, all portions of the fastening member having, in the form now being described, like cross sections. While such is not necessary, we 10 preferably employ for the material of the fastening member spring steel as with its use we obtain certain hereinafter mentioned advantages which are very desirable in our 15 plug. It will be seen that, in the forms shown, we have not knocked off the portions 16 of the fastening member from the axis of the portions 15 in the plane of the main portion 14 of said member, but have 20 knocked said portions 16 off in a plane at an angle of about 45 degrees to the plane in which the main portion 14 extends from the inwardly turned portions 15. The reason for this relationship will better appear in a 25 description of the operation of the plug.

The form of fastening member may be varied and to illustrate we have shown another form in Figs. 6 and 7 in which the fastening member is formed from spring steel 30 stock of elliptical cross section bent into U shape and its ends merely turned inwardly in alinement and at their points, where inwardly turned merely given a twist of 45 degrees so that the major axis of the inwardly turned portions will be at such angle 35 of 45 degrees from the direction of the main portion 14'. The main portion of this fastening member is bent U shape in the direction of the major axis of its elliptical cross 40 section. For all practical purposes a fastening member so made from spring steel of elliptical cross section and without making the additional bend or set off 16 as in the form of Figs. 4 and 5, operates similarly 45 for the purposes of our plug and a fastening member of either form will suffice. The inwardly turned portions of the fastening member made from the elliptical stock and shown in Figs. 6 and 7 are designated by 50 reference character 15'.

The insulator of our plug is shown designed in different ways. In the preferred form shown in Figs. 1 and 3 it is provided exteriorly and above the downwardly facing 55 shoulder with a peripheral turned away portion or groove 18 preferably extending completely around the insulator. At the deepest portion of this groove there are located short preferably diametrically opposite 60 transversely extending holes 19 to the bottom of one of which preferably runs the second electrode 10 as shown in Figs. 1 and 3. While these may be omitted, we preferably line the interior of the holes 19 with 65 metal sleeves 20 which may be cemented in

place and these sleeves serve to receive directly pressure from the fastening member and communicate it to the material of the insulator resulting in more of a distribution of the pressure from the fastening member 70 over a greater locality of the insulating material with the idea of decreasing the danger of breakage of the insulator by reason of the localization of all the pressure of the fastening member on the insulator in substantially two localities. While the use of the sleeves 20 may in some cases with some grades of insulating material, improve the service of the plug they are in many cases not at all necessary or advisable. Where 80 they are used however, the upper end of the second electrode 10 may contact with one of these sleeves as shown in Figs. 1 and 3. In Fig. 8 there is shown a design in which these sleeves 20 are omitted and in this form 85 in order not to weaken the insulator directly beneath either of the holes 19, the second electrode 10 does not run up to the bottom of its adjacent hole 19 but up at one side of the hole so that it may pierce the hole at 90 one side and there make electrical connection with the metallic fastening member when the latter is holding the insulator in place in the bushing. In this view the holes are numbered 19' and the second electrode 95 10.

In the forms of Figs. 1, 3, and 8 we preferably permanently attach the fastening member to the insulator, that is so it remains fast to the insulator in all use of the 100 plug though it may be conveniently removed therefrom if desired. As stated above, the fastening member is preferably formed from spring steel material and when so constructed the fastening member may be readily sprung 105 to locate its ends in the holes 19' of the insulator of Fig. 8 or in the interior of the sleeves 20 of the form of insulator of Figs. 1 and 3 and when so located in these holes or sleeves the action of the spring material will prevent 110 any undesired removal of the fastening member from the insulator. While having also another function, the peripheral groove 18 in the insulators are useful in decreasing the amount of springing the fastening member would otherwise have to do in putting it in place on the insulator as it is in some cases desirable that the ends of the fastening member project into the insulator sufficiently to meet the second electrode 10 which 115 in some cases it is most desirable to extend parallel of the axis of the insulator and not be deflected outwardly as shown in the form of Fig. 10. In cases where the second electrode extends parallel to the axis of the insulator and where a rather wide shoulder 6 is used on the insulator, if the groove 18 or some other form of recess is not formed adjacent the holes 19, it would in some cases 120 be hard to get the fastening member to 130

spring sufficiently without breaking, to get it in place properly on the insulator. It is furthermore advantageous to have the fastening member contact with the insulator for downward pressure at some distance from the place where the fastening member engages the bushing as this arrangement will give some length of the material of the fastening member between the point of engagement with the bushing and the point of engagement with the insulator, thus providing for desirable spring in the fastening member between these points to aid in taking up inaccuracies in the manufacture of the different parts without affecting the operation of securing the insulator in place in the bushing firmly. With this desirable spring in the fastening member the insulator is held against its seat with a somewhat yielding though firm pressure and this we find an advantage with our spark plug in decreasing the breakage of the insulators when hot from use over when they are held downwardly against their seat by a more positive fastening means, particularly when using no gaskets between the shoulder 6 on the insulator and the shoulder 4 on the bushing but instead ground or otherwise smoothed surfaces on these shoulders as we show in all the forms of the drawings.

The plug of Figs. 1 to 3 is assembled after the bushing 1 is screwed into place in the engine casing if desired, by taking the insulator with the fastening member attached, as shown in Fig. 3 and with the main portion of the fastening member turned up along the side of the insulator, placing the insulator down endwise into the hollow bushing and with the portions 15 of the fastening member passing downwardly in the entrance portions 12 of the diametrically opposite slots in the top of the bushing. After the insulator is sufficiently lowered for the portions 15 of the fastening member to reach the substantially horizontal portions of these slots, the insulator with the fastening member is turned to carry the portions 15 of the fastening member into the horizontal portions of the slots and, if desired, until these portions 15 engage the upper surfaces of these horizontal slots when the shoulder 6 of the insulator is resting on the internal shoulder 4 in the bushing. The insulator may then be securely forced against the seat in the bushing by merely swinging the main portion 14 of the fastening member down about its bearings in the bushing to about 45 degrees from a depending position in alignment with the axis of the plug when the insulator will be firmly and securely held against its seat in the bushing, for by such swinging action the eccentricity of the portions 15 of the fastening member which engage in the slots in the bushing, to 65 the portions 16 which work in the holes in

the insulator, causes the insulator to be forcibly engaged against its seat in the bushing to which position it will be held by the fastening member when the fastening member is so swung down, by reason of the portions 16 then being beneath the portions 15 or so nearly so that there is no force acting in the proper direction on these parts to overcome the existing friction or inertia and cause the fastening member to be swung 75 back upwardly to its original position in which it was inserted, and relieve the cam or eccentric pressure on the insulator. In this action just described, the resilient nature of the fastening member comes well into play 80 though it may be dispensed with if the parts are sufficiently accurate in construction. We prefer to use the fastening member made from spring material but when so constructed it is perfectly practical to omit any inclination in the upper surfaces of the horizontal portions of the slots in the bushing as all necessary tolerance in the manufacturing of the various parts can well be taken care of by the elasticity in the fastening member. 85 Should we omit the elasticity in the fastening member due to the use of spring stock we prefer to use the inclines on the upper surfaces of the horizontal portions of the slots in the bushing for, with them provided, 90 an adjustment of the parts can be effected by rotating the insulator until the portions 15 of the fastening member engages these surfaces whereupon the fastening member may then be swung down with a surety in 100 the complete seating action of the insulator against its seat which surety might not always exist if the parts were not always made accurate without any substantial elasticity in the fastening member or any preliminary adjustment possible by means of the inclined surfaces on the bushing slots or some equivalent. If there is substantially no spring in the fastening member the effective throw of the eccentricities on the fastening 105 member would have to be considerably less. Also it will be observed that by the use of spring material in the fastening member that as the portions of it inside of the bushing bearings bend or yield as the fastening 110 member is swung down, the eccentricity of the fastening member will accordingly decrease thus enhancing the leverage of the fastening member over what it would otherwise be for as it springs the eccentricity of 115 its bearings accordingly decreases with a resultant increase-magnification of the mechanical advantage of the fastening member as a pressure applying means. It is of course true that the mechanical advantage 120 would gradually increase with the fastening member non-elastic but by being also yielding and of eccentric construction the increase of mechanical advantage is greatly augmented. 125 130

To remove the insulator from the bushing the reverse of the above operation is merely used and it will be seen that this can readily be done without the use of any wrench or tool by merely catching the fastening member with the fingers and pulling it upward, then giving the insulator a slight turn, and removing it axially of the bushing. The operation of assembling the plug is also done similarly without a wrench or tool. The fastening member remains attached to the insulator in this form, when the plug is disassembled and is not liable of being misplaced and lost. It will be seen that when the plug is assembled the fastening member is in electrical connection with the second electrode either by engaging the upper end of it directly as in the form of insulator of Fig. 8, or by engaging the sleeve 20 which engages the electrode in the form of Figs. 1 and 3. In either form the fastening member by engaging the bushing conducts the return current to the latter from which it returns to the battery or magneto through the engine as is common. The wire connected to the upper end of the other electrode 7 leads to the other side of the battery or magneto in the usual manner. If but one electrode is to be carried by the insulator the wire 10 in the latter is omitted and the other electrode is carried by the lower end of the bushing in the usual way, as shown in connection with Fig. 9.

The operation of the fastening member is substantially the same when the fastening member is formed from elliptical stock as shown in Figs. 6 and 7. The variable diameter of the inwardly turned portions which bear on the insulator and the bearings of the bushing provides a cam action which, as the fastening member is swung down, cams the insulator firmly against its seat in the bushing. A similar springing action takes place when the member is made from spring stock and a similar augmentation of the mechanical advantage of the fastening member occurs as the fastening member springs between its points of engagement with the insulator and the bushing. In this form the fastening member may be made from relatively rigid stock under the same conditions as with the more eccentric construction.

In Fig. 9 we have shown a form in which the fastening member is not carried by the insulator but is a separate element removable and replaceable as such. The insulator is shown carrying but the one central electrode 7 and the other electrode 10" projects from the lower end of the bushing in the usual way. Otherwise the bushing is the same as the forms heretofore described. The insulator is minus the transverse holes for the fastening member and the peripheral groove, but it is provided with an upwardly

facing shoulder 21 the upper surface of which corresponds to the bottom of the transverse holes in the forms just described. In assembling this plug the insulator is placed in position in the bushing with its lower facing shoulder 6 resting on the upwardly facing shoulder 4 in the bushing. The fastening member is then lowered in place through the slots 12; then turned slightly axially to engage the portions 15 in the horizontal portions of the slots, the extreme inner ends of the fastening member being located above the shoulder 21 on the insulator. When the parts are in this position the fastening member is swung downward as in the other forms which results in the insulator being, as before, forced firmly against its seat in the bushing. The eccentric or camming action of the fastening member is in all respects the same as in the hereinbefore described operations of the other forms. Reversal of the operation releases the insulator and frees the fastening member for removal after which removal the insulator may be freely lifted out. If desired a metal band may rest on the shoulder 21 permanently and, if it is desired that the insulator of this form carry both electrodes the second one may extend downward from this band to the lower end of the insulator, the band electrically connecting the second electrode with the fastening member.

Fig. 10 shows a still different form in which the fastening member is carried permanently by the insulator as with the form of Figs. 1 and 3 but it is so carried directly by a metal band 22 resting on a shoulder 23 on the insulator and held in place on the insulator by being crimped inwardly at 24 beneath a peripheral ridge on the insulator. For the purpose of this crimping the upper end of the metal band is provided with a thin fin 25. This band is provided with diametrically opposite holes 26 for receiving the ends of the fastening member as do the holes 19 of the form of Figs. 1 and 3. These holes are counterbored at 27 to leave a length of the fastening member between the bushing and the point of engagement with the band for the purpose of making the member more yielding, as has been heretofore noted to be desirable in connection with the description of the other forms. The second electrode in this form may run to the shoulder 21 on the insulator and there contact with the band 22 which engages the fastening member 14 which electrically connects with the bushing when the plug is assembled. In this form the operation and action is the same as with the form of Figs. 1 and 3 the band and fastening member remaining attached to the insulator, the band merely reinforcing the insulator mechanically in clamping the insulator in place.

In all the forms heretofore described a bushing has been referred to but in Fig. 12 we have shown the insulator seating directly in an opening in the engine casing. In this 5 way the separate bushing may be eliminated and the wall of the engine receives the insulator directly. All that is necessary to do this is to form a proper seat 30 in the wall of the engine upon which the shoulder of 10 the insulator is to rest and also to provide upstanding ears or hooks 28 under which the portions 15 of the fastening member may engage. Then by placing the insulator against its seat, turning it so that the fastening member portions 15 will come beneath the hooks 29 and subsequently swinging the fastening member 14 the insulator will be forced firmly against its seat and held there as before. To remove the insulator the reversal of this operation is carried out. The 15 fastening member may or may not be permanently attached to the insulator in this manner of using our insulator as with the other forms. It is necessary however to so 20 locate the cams or eccentric portions of the fastening member to be used in this way, that the insulator will be forced to its seat by the time the main portion of the fastening member will engage the engine casing, 25 as the insulator in the form shown without the bushing will not be carried so high away from the engine casing as where the bushing is used. It is preferable that the insulator be properly fastened to its seat in 30 the bushing when the main or handle portion of the fastening member is depending about 45 degrees from a vertical dropped from its bearings in the plug, yet this will 35 vary under different circumstances and it is 40 obvious that the offset of the eccentrics or location of the effective cam portion can be made and located as desired to suit the circumstances and conditions under which the plug is to be used which conditions may 45 sometimes vary in different engines in which it is desired to use the plugs.

We have shown no gasket between the shoulder 6 of the insulator and the shoulder 4 of the bushing as we prefer to use merely 50 a ground or other smoothed joint here but it is to be understood that instead of a ground joint a gasket of any suitable form may be used this not affecting the patentable principles of our plug. Other numerous ob- 55 vious changes in the designs of our plug which we have shown merely for illustrative purposes, will no doubt occur to those skilled in the art and we do not confine our protection to the details of design shown except as 60 required by the scope of the appended claims.

Having described our invention what we claim as our invention and desire to secure by Letters Patent is:

65 1. In a spark plug for internal combustion

engines, the combination of a bushing; an electrode carrying insulator adapted to removably seat therein; and a fastening member having alined inwardly turned ends for coöperating with the bushing and the insulator to fasten the latter to its seat in the former when the fastening member is rotated about the axis of the inwardly turned portions. 70

2. In a spark plug for internal combustion engines, the combination of a bushing; an electrode carrying insulator adapted to removably seat therein; and a fastening member having alined inwardly turned ends a portion of said ends being farther from the 80 axis of rotation of the fastening member than are other portions whereby when the fastening member is rotated about the axis of the inwardly turned ends with such portions in coöperation with the bushing and 85 the insulator, the insulator will be forced to its seat in the bushing.

3. In a spark plug for internal combustion engines, the combination of a bushing; an electrode carrying insulator adapted to removably seat therein; and a fastening member having opposed projections for forcing the insulator to its seat in the bushing when the fastening member is rotated. 90

4. In a spark plug for internal combustion engines, the combination of a bushing; an electrode carrying insulator adapted to removably seat therein; and a fastening member having a plurality of projections extending over portions of the insulator 100 adapted when the fastening member is rotated about bearing surfaces on the bushing and about an axis at an angle to the longitudinal axis of the plug, to force the insulator against its seat in the bushing. 105

5. In a spark plug for internal combustion engines, the combination of a bushing; an electrode carrying insulator adapted to removably seat therein; and a fastening member having a plurality of projections extending over portions of the insulator adapted when the fastening member is rotated about a plurality of diametrically opposite bearing surfaces on the bushing, and 110 about an axis at an angle to the longitudinal axis of the plug, to force the insulator against its seat in the bushing. 115

6. In a spark plug for internal combustion engines, the combination of a bushing; an electrode carrying insulator adapted to removably seat therein; and a fastening member having a plurality of portions for engaging a plurality of peripherally separated bearing surfaces on the bushing, and having a plurality of portions adapted to project 120 over a plurality of peripherally separated portions of the insulator, whereby when the fastening member is rotated with its corresponding portions in engagement with the bearing surfaces on the bushing and its 125

other mentioned portions projecting over the insulator, the insulator will be forced against its seat in the bushing.

7. In a spark plug for internal combustion engines, the combination of a bushing; an electrode carrying insulator adapted to removably seat therein; and a fastening member having a plurality of portions for engaging a plurality of peripherally separated bearing surfaces on the bushing, and having a plurality of portions adapted to project over a plurality of peripherally separated portions of the insulator, whereby when the fastening member is rotated about an axis 10 at an angle to the longitudinal axis of the plug, with its corresponding portions in engagement with the bearing surfaces on the bushing and with its other mentioned portions projecting over the insulator, the insulator will be forced against its seat in the latter.

15 8. In a spark plug for internal combustion engines, the combination of a bushing; an electrode carrying insulator adapted to removably seat therein; and, a fastening member having separated portions adapted to project between the bushing and insulator at peripherally separated points of the plug, said portions constructed so that rotation of the fastening member about an axis at an angle to the longitudinal axis of the plug will cause relative movement between the insulator and bushing to force the former against its seat in the latter.

25 9. In a spark plug for internal combustion engines, the combination of a bushing; an electrode carrying insulator adapted to seat therein; and a fastening member adapted to straddle the plug and having separated portions adapted to project between the bushing and insulator at peripherally separated points of the plug, said portions constructed so that rotation of the fastening member about an axis passing through the separated portions of the fastening member will cause relative movement between the insulator and bushing to force the former against its seat in the latter.

35 10. In a spark plug for internal combustion engines, the combination of a bushing; an electrode carrying insulator adapted to seat therein; and a fastening member adapted to straddle the bushing and insulator at peripherally separated points of the plug, said portions constructed so that rotation of the fastening member about an axis passing through the separated portions of the fastening member will cause relative movement between the insulator and bushing to force the former against its seat in the latter.

45 11. In a spark plug for internal combustion engines, the combination of a bushing; an electrode carrying insulator adapted to removably seat therein; and a fastening member adapted to straddle the bushing and having separated portions adapted to project through the wall of the bushing and over peripherally separated portions of the insulator, said portions of the fastening member constructed so that rotation of the fastening member about an axis passing through the portions of the fastening member will cause relative movement between the insulator and the bushing to force the former against its seat in the latter.

55 12. In a spark plug for internal combustion engines, the combination of a bushing; an electrode carrying insulator adapted to removably seat therein; and a fastening member adapted to straddle the bushing and having separated portions adapted to project over a portion of the insulator and so constructed that when

an electrode carrying insulator adapted to removably seat therein; and a fastening member adapted to straddle the insulator and having separated portions permanently engaging the insulator at peripherally separated points and portions for detachably engaging bearings in the bushing, whereby when the fastening member is rotated when in co-operative relationship with the bearings in the bushing, and about an axis at an angle to the longitudinal axis of the plug, relative movement between the insulator and the bushing will take place to force the former against its seat in the latter.

60 13. In a spark plug for internal combustion engines, the combination of a bushing provided with an internal seat and peripherally separated L shaped slots at its upper end; an electrode carrying insulator adapted to removably seat therein against said internal seat; and a fastening member adapted to straddle the bushing and having separated portions adapted to pass down through the vertical portions of the L shaped slots and into the horizontal portions of the same and to extend over peripherally separated portions of the insulator, the construction of the separated portions of the fastening member being such that rotation of the fastening member about an axis passing through its separated portions when said member is in place in the horizontal portions of the slots, will cause relative movement between the insulator and the bushing and cause the former to be forced against its seat in the latter.

65 14. In a spark plug for internal combustion engines, the combination of a hollow bushing having an internal seat and L shaped slots at its upper end; an electrode carrying insulator adapted to removably seat therein; and a fastening member straddling the insulator and rotatively carried by the latter at a plurality of peripherally separated points and adapted to detachably engage in the L shaped slots in the bushing, the construction of the fastening member being such that rotation of the fastening member about its connections with the insulator when the latter is in place in the bushing and the fastening member in engagement with the horizontal portions of the L shaped slots will cause relative movement between the insulator and the bushing so as to force the former against its seat in the latter.

70 15. In a spark plug for internal combustion engines, the combination of a hollow bushing having an internal seat and L shaped slots opening at one end of the bushing; an electrode carrying insulator adapted to removably seat against the seat in the bushing; and a fastening member adapted to be removably placed in the L shaped slots with a portion projecting over a portion of the insulator and so constructed that when

rotated when in such position, about an axis at an angle to the longitudinal axis of the plug, relative movement between the insulator and the bushing will be effected to force the former against its seat in the latter.

15. In a spark plug for internal combustion engines, the combination of a hollow bushing having an internal seat and provided with peripherally separated bearing surfaces, points of which are greater distances from said seat than are other points; an electrode carrying insulator adapted to be removably seated in said bushing; and a fastening member provided with inwardly turned ends, portions of which are adapted to bear upon the said bearing surfaces in the bushing and other portions of which are adapted to project over and bear upon the insulator to force the latter to its seat in the bushing when the fastening means is rotated about the inwardly turned ends.

16. In a spark plug for internal combustion engines, the combination of a bushing having an internal seat and peripherally separated slots open at their upper ends and forming inclined bearing surfaces points of which are at greater distances from said seat than are other points; an electrode carrying insulator adapted to removably seat in the bushing; and a fastening member provided with inwardly turned ends rotatable about an axis at right angles to the axis of the insulator, portions of which ends are adapted to bear upward on such bearing surfaces on the bushing and other portions which are adapted to project over and bear downwardly on the insulator to force the latter to its seat in the bushing.

17. In a spark plug for internal combustion engines, the combination of a bushing having peripherally separated L-shaped slots at its upper end, the upper surface of the horizontal leg of said slot being inclined downwardly from the vertical leg to allow for the vertical adjustment of a fastening member; an electrode carrying insulator adapted to removably seat in said bushing; and a fastening member having inwardly turned ends adapted to pass downwardly through the vertical portions of the slots into the horizontal portions and adapted to bear upwardly on said inclined portions of said slots and downwardly on peripherally separated portions of the insulator so that when the fastening member is rotated about the axis of said ends the insulator is forced against its seat in the bushing.

18. In a spark plug for internal combustion engines, the combination of a bushing; an electrode carrying insulator adapted to removably seat therein; and a yielding fastening member having separated portions adapted to project between the bushing and the insulator at peripherally separated points of the plug, said portion so constructed

ed that rotation of the fastening member about an axis at an angle to the longitudinal axis of the plug will cause relative movement between the insulator and bushing to force the former against its seat in the latter.

19. In a spark plug for internal combustion engines, the combination of a member having an opening to receive a spark plug insulator; an electrode carrying insulator adapted to removably seat therein; and a fastening member having separated portions adapted to project between the first mentioned member and insulator at peripherally separated points of the latter, said portions constructed so that rotation of the fastening member about an axis at an angle to the longitudinal axis of the insulator will cause relative movement between the insulator and first mentioned member to force the former against its seat in the latter.

20. In a spark plug for internal combustion engines, the combination of a bushing having peripherally separated bearings and an internal seat; an electrode carrying insulator having a horizontal groove extending about its periphery and adapted to removably seat in the bushing and a fastening member having inwardly turned ends adapted to extend through the bearings in the bushing and to engage bearing holes extending inwardly of the insulator from the depth of said peripheral groove, said fastening member constructed so that rotation of it when the parts are as assembled will cause the insulator to be forced against its seat in the bushing.

21. An insulator for internal combustion engines having diametrically disposed bearings with the ends of a fastening member mounted therein, an electrode passing from one or more of said bearings to the end of the insulator forming one spark terminal, and a second electrode extending longitudinally through the insulator and forming another spark terminal.

22. In a spark plug for internal combustion engines, the combination with an electrode carrying insulator, of a bushing having bearing openings and a seat for the insulator, and a fastening member having inwardly turned yielding ends cooperating with the bearing openings and the insulator for attaching the insulator to the seat in the bushing when the ends are rotated by movement of the fastening member.

23. In a spark plug for internal combustion engines, the combination with an insulating core, of a bushing having diametrically opposite bearings and an internal seat for the insulating core, and a fastening member comprising two portions to be interposed between said bearings and the insulator and then rotated by movement of the fastening member, said portions being so constructed as when rotated to yieldingly

hold the core against the seat in the bushing.

24. In a spark plug for internal combustion engines, the combination with an electrode carrying insulator, of a bushing having diametrically opposite bearing openings and an internal seat for the insulator, and a fastening member having inwardly turned ends rotatable in the aforesaid bearings and formed to coöperate with the insulator to yieldingly hold the insulator against its seat in the bushing when the fastening member is moved to a certain position. 70

25. In a spark plug for internal combustion engines the combination of a fixed member having a seat and an opening, an electrode carrying insulator adapted to pass into the opening and against the seat, and a single manipulatively operable yielding pressure applying element for forcing the insulator against its seat in the fixed member and holding it there in opposition to pressure exerted from the engine chamber when the plug is in use in the same. 80

26. A spark plug comprising a fixed member having an opening and a seat for an insulator, an electrode carrying insulator adapted to pass into the opening and against the seat, and a fastening member disposed transversely in the insulator, and means whereby the fastening member may be manually operated to exert a yielding pressure on the insulator to force the same firmly against its seat in the fixed member. 85

27. In a spark plug the combination of a bushing, an electrode carrying insulator adapted to seat therein, and rotatable yielding pressure applying means adapted to rotate about an axis at an angle to the longitudinal axis of the insulator in coöperation with the insulator and bushing, to force the insulator against its seat in the bushing. 100

28. In a spark plug the combination of a bushing, an electrode carrying insulator adapted to seat therein, and a rotatable yielding fastening member for forcing the insulator against the seat in the bushing when the fastening member is rotated when in coöperation with the insulator and bushing. 110

29. In a spark plug, the combination of a bushing, an electrode carrying insulator adapted to seat in connection therewith, and a rotatable resilient member rotatably co-operating with the insulator and bushing about an axis at an angle to the longitudinal axis of the insulator, said axis being on a line that will pass through the projected transverse area of the insulator, said resilient member serving when rotated to force the insulator against its seat. 115

30. In a spark plug, a bushing, an electrode carrying insulator adapted to seat in the bushing, and a crank like resilient member rotatably engaging with the bushing 120

and insulator and serving when rotated to force the insulator against its seat in the bushing and to hold it there by reason of the crank like member assuming a substantially "dead center" relationship between the insulator and bushing. 75

31. In a spark plug, a bushing member, an insulator member carrying an electrode and adapted to seat therein, and a resilient member rotatable about an axis at an angle to the axis of the other members and fulcruming against one of the first mentioned members and acting against the other in substantially alining but oppositely directed lines of action passing through points close to the fulcrum point, whereby the moment of force tending to rotate the rotatable member through the reaction of the first said members will be too small to overcome the frictional resistance against the resilient rotatable member. 85

32. In a spark plug, a bushing, an electrode carrying insulator adapted to seat therein, and a cam like yielding fastening member adapted to be rotated to apply a gradually increasing yielding pressure of the insulator against its seat in the bushing. 90

33. In a spark plug, a bushing, an insulator adapted to seat therein and carrying an electrode, and rotatable fastening means attachable to the insulator and insertible therewith in the bushings, said insulator and fastening member being rotatable axially of the bushing to bring the fastening member into engagement with bearing surfaces on the bushing and said fastening member adapted then to be rotated about an axis transverse to the longitudinal axis of the plug to thereby by the cam like construction of the fastening member, force the insulator more firmly against its seat in the bushing. 100

34. In a spark plug, a bushing, an electrode carrying insulator adapted to seat therein, and a fastening member for securing the insulator in the bushing, arranged for permanent and yielding attachment to the insulator, said fastening being adapted to serve to press the insulator to its seat in the bushing when operated in coöperation with the insulator and bushing. 110

35. An article of manufacture comprising an electrode carrying insulator for spark plugs, and having a fastening member rotatably engaging therewith at a plurality of separated points to serve to fasten the insulator in the bushing of a spark plug when the insulator and fastening means are brought into operative relationship with the bushing and the fastening means operated. 120

36. In a spark plug, a bushing, an electrode carrying insulator adapted to seat therein, and a yielding fastening means for holding the insulator against its seat in the bushing, said yielding means directly en- 130

gaging the insulator and bushing and being manually manipulative to apply a yielding pressure on the same.

37. In a spark plug, the combination of 5 a relatively fixed member; an electrode carrying insulator adapted to removably seat therein; and an element carried by said insulator and movable therewith into coöperative relationship with said fixed member; 10 and adapted to be rotated about an axis transverse to the axis of the insulator to apply pressure to lock it to its seat.

38. In a spark plug, the combination of a 15 relatively fixed member, an element including an electrode carrying insulator adapted to removably seat therein, and a single member rotatable about an axis transverse to the axis of the insulator to apply a yielding pressure from said element to the fixed 20 member to lock said element in its seat.

39. In a spark plug, the combination of a 25 relatively fixed member; an electrode carrying insulator adapted to removably seat therein; and an element fulcruming on a bearing surface and acting on said insulator to apply pressure to force it to its seat, provision being made whereby the distance of 30 said bearing surface from said seat may be varied.

40. In a spark plug, the combination of 35 a relatively fixed member, an electrode carrying insulator adapted to removably seat therein and an element fulcruming on a bearing surface and extending over a por-

tion of the insulator, said element being 35 adapted to be actuated so as to apply pressure to said insulator to force it to its seat, provision being made whereby the distance of said bearing surface from said seat may be varied.

41. As an article of manufacture, an electrode carrying insulator for spark plugs 40 adapted to seat in a bushing and provided with a fastening member yieldingly engaging the insulator so as to be removable therefrom, said fastening member being adapted to lock the insulator to its seat in the bushing when operated in coöperation with the insulator and bushing.

42. An article of manufacture comprising 45 an electrode carrying insulator adapted to removably seat in a bushing and provided with a peripheral groove and a fastening member yieldingly engaging said insulator at points in said groove whereby said fastening member is removable from said insulator said fastening member being adapted to lock the insulator to its seat in the bushing when it is operated in coöperation with the insulator and bushing.

In testimony whereof we affix our signatures in the presence of two witnesses.
